UNITED STATES PATENT OFFICE.

HENRY H. LANG, OF ERIE, PENNSYLVANIA, ASSIGNOR TO JENNIE D. LANG,
OF ERIE, PENNSYLVANIA.

IRONING-BOARD.

SPECIFICATION forming part of Letters Patent No. 727,810, dated May 12, 1903.

Application filed August 28, 1902. Serial No. 121,303. (No model.)

To all whom it may concern:

Be it known that I, HENRY H. LANG, a citizen of the United States, residing at Erie, in the county of Erie and State of Pennsylvania, have invented certain new and useful Improvements in Ironing-Boards; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

My invention relates to improvements in ironing-boards, and has for its object the construction of an ironing-board supported upon folding legs and provided with a bosom-board in such a manner that it can be laid over upon said ironing-board for use or folded beneath the same when not in use.

My invention is hereinafter more fully set forth and explained, and illustrated in the accompanying drawings, in which—

Figure 1 is a side view in elevation of an ironing-board embodying my invention. Fig. 2 is a top or plan view of the same. Fig. 3 is a side view in elevation, showing the same folded up.

In the drawings thus illustrating my invention, A is an ironing-board. B and B' are the legs thereof, pivoted thereto by means of a pivot b and pivoted together by the pivot b'. A' is a rack secured to the under side of the ironing-board A and adapted to engage the upper end of the legs B', whereby the height of the ironing-board A can be adjusted to suit the operator, all of which parts are of the usual and ordinary construction.

To the rear end of the under side of the ironing-board A, I secure a pivot c, to which are pivoted links C', which pass up through open slots E E, cut in the end of the board A, and to the opposite ends of said links C' I pivot the rear end of a bosom-board C by means of pivots c'. It will be seen that these pivots c and c' and the links C' will support the rear end of a bosom-board and permit it to be in either the position shown in full lines in Figs. 1 and 2 or hanging down, as shown in dotted lines in Fig. 1, or folded back, as shown in Fig. 3.

Near the rear end of the under side of the bosom-board C, I secure a support D for the purpose of keeping the bosom-board raised above the ironing-board, as shown in Fig. 1.

Having thus shown and described my invention, so as to enable others skilled in the art to which it appertains to construct and use the same, what I claim as new, and desire to secure by Letters Patent of the United States, is—

The combination of an ironing-board having slots in the rear end thereof, links pivoted to the under surface of the rear end of the ironing-board so as to pass up through the slots therein, a bosom-board pivoted at its rear end to the upper ends of said links, and a support between said ironing and bosom boards, substantially as set forth.

In testimony whereof I affix my signature in presence of two witnesses.

HENRY H. LANG.
